UNITED STATES PATENT OFFICE.

JOHN F. ROSS, JR., AND TIMOTHY C. BILLUPS, OF NORFOLK, VIRGINIA.

COIN CABINET.

Application filed June 9, 1928. Serial No. 284,153.

The present invention relates to a coin cabinet, for storing coins and has for its object to provide a structure with a plurality of drawers therein, the drawers being divided 5 into compartments for holding coins of different denominations in predetermined groups, whereby a teller in a bank may easily and readily make change and accurately check up at the end of the business day.

10 Another very important object of the invention resides in the provision of a cabinet of this nature, including a plurality of drawers in a cabinet, and means for holding the drawers against total displacement from the 15 cabinet, in an accidental manner, but said means being operable to allow the removal of the drawers so that they may be stacked in a safe over night.

A still further very important object of 20 the invention resides in the provision of a cabinet of this nature which is simple in its construction, strong and durable, inexpensive to manufacture, thoroughly efficient and reliable in use, and otherwise well adapted for 25 the purpose for which it is designed.

With the above and numerous other objects in view, as will appear as the description proceeds, the invention resides in certain novel features of construction, and in the combination and arrangement of parts as will 30 be hereinafter more fully described and claimed.

In the drawings:

Figure 1 is a front elevation of the cabinet 35 embodying the features of our invention.

Figure 2 is a side elevation thereof, showing a portion of one side wall broken away.

Figure 3 is a perspective view of the locking panel.

Figure 4 is a horizontal section through the cabinet showing one of the drawers in top plan.

Figure 5 is a transverse vertical section through said drawer.

Figure 6 is a top plan view of another drawer.

Figure 7 is a top plan view of a third drawer.

Figure 8 is a sectional view therethrough 50 taken substantially on the line 8—8 of Figure 7, and

Figure 9 is a top plan view of a fourth drawer.

Referring to the drawings in detail, it will 55 be seen that the cabinet includes a bottom 5, side walls 6, and a back 7 rising therefrom,

and a top 8. A plurality of horizontal partitions 9 are disposed in spaced parallelism above the bottom 5 and in respect to each other and the top 8. A plurality of drawers 60 10, 11, 12, and 13, are mounted to slide in the compartments formed by the partitions 9, the drawers 10, 11, and 12 being slideable on the partitions and the drawer 13 being slideable on the bottom. One side 6 is provided 65 with a vertical slot 14 for receiving a panel 15, which is hingedly mounted as at 16, and has a knob 17. On the inner face of this panel are a plurality of inwardly directed lugs on faces 19, screwed or otherwise secured as at 70 20, to the panel. The adjacent sides of the drawers 10, 11, 12 and 13 are provided with longitudinally extending grooves 21 into which the lugs extend, to limit the outward movement of the drawers when the panel is 75 in a closed position and thus the drawers cannot be totally removed when the grooves 21 terminate a distance from the ends thereof.

The drawers are provided with suitable handles 22 so that they may be conveniently 80 withdrawn when desired.

When it is desired to take the drawers out of the cabinet, the panel 15 is swung to an open position, thus removing the lugs 18 from the grooves 21.

The drawer 10 has a grate-like frame 25, mounted therein, said frame providing a plurality of openings 26, to receive stacks of dimes on edge, each stack equal to one dollar. This frame is further provided with 90 openings to provide compartments 27 for receiving stacks of dimes, which stack is equal to two dollars. The frame is further provided with openings providing compartments 28 to receive stacks of nickles, each stack being 95 equal to fifty cents. The frame is further provided with openings 29 to receive stacks of nickels, each stack being equal to one dollar.

In the present illustration, it will be seen 100 that if the drawer is full, the total amount would be one hundred and thirteen dollars, divided into thirty-three dollars in dimes in one dollar stacks, forty-two dollars in dimes in two dollar stacks, eighteen dollars in 105 nickles in fifty cent stacks, and twenty dollars in nickles in one dollar stacks.

In the drawer 11 there is a grate like frame 30 having openings forming compartments 31 and the drawer will hold three hundred 110 dollars in quarters.

The drawer 12 has a frame 32 with openings

33 therein forming compartments to receive stacks of half dollars, each stack consisting of twenty half dollars and the drawer holds a total of five hundred dollars.

5 The drawer 13 has a frame 34 therein, with a group of openings 35, to form compartments for receiving twenty dollar gold pieces, in stacks on edge, each stack totalling two hundred dollars. The frame 34 is provided with 10 a group of openings 36 to receive ten dollar gold pieces, twenty to a stack. The frame is provided with compartments 37 to receive five dollar gold pieces, twenty to a stack. The frame is provided with openings 38 to receive 15 two dollar and a half gold pieces twenty in a stack. The frame is provided with openings 39 to receive silver dollars, ten in a stack. The frame is provided with openings 40 to receive pennies, twenty five in a stack, and 20 with an enlarged compartment 41 to receive odd gold pieces. This drawer will hold twelve hundred dollars in twenty dollar gold pieces, eight hundred dollars in ten dollar gold pieces, four hundred dollars in five dollar 25 gold pieces, four hundred and fifty dollars in two and a half dollar gold pieces, one hundred and sixty dollars in silver dollars, and five dollars and twenty-five cents in pennies, being a total of thirty hundred and fifteen dollars and twenty-five cents.

From the above detailed description it will be readily apparent that this cabinet is designed principally for use in teller's cages in banks. It conserves a good portion of the 35 usually limited space in such cages, by doing away with the present method of handling coins of various denominations in trays set out at random, consolidating them into space required for one of the trays. The drawers 40 of this cabinet, being of uniform size, are to be removed at the end of the day, stacked upon each other, and placed in the vault over night. The sides of these drawers are of the proper height to permit stacking without interfering with the coins therein. The tellers, when 45 balancing cash at the end of the day, or whenever necessary, may by glancing at the number immediately in front of the first stack in each section and by totalling these amounts, 50 determine the cash in the cabinet much more readily than by having to count each stack separately.

It is thought that the construction, utility, 55 operation, and advantages of this invention will now be quite apparent to those skilled in

this art, without a more detailed description thereof. The present embodiment of the invention has been disclosed in detail, merely by way of example, since in actual practice it attains the features of invention enumerated as desirable in the statement of the invention and the above description. 60

It will be apparent that changes in the details of construction, and in the combination and arrangement of parts may be resorted to, 65 without departing from the spirit or scope of the invention as hereinafter claimed or sacrificing any of its advantages.

Having thus described our invention, what 70 we claim as new is:

1. In combination, a cabinet, a plurality of drawers slideable in the cabinet, a panel hingedly mounted in the side of the cabinet, and means on the panel to limit the sliding movement of the drawers when the panel is closed and to be free therefrom when opened. 75

2. In combination, a cabinet formed with a plurality of drawer receivable compartments, drawers slideable in the compartments, one side of the cabinet having a slot, a panel hinged to the said side of the cabinet to swing 80 it to the slot, the sides of the drawer adjacent the panel being provided with longitudinal grooves, and lugs on the panel to extend into the grooves when the panel is closed, so as to limit the movement of the drawers, and whereby the panel may be swung to an open position to allow the drawers to be totally removed from the cabinet. 85

3. In combination, a cabinet formed with a plurality of drawer receivable compartments, drawers slideable in the compartments, one side of the cabinet having a slot, a panel hinged to the said side of the cabinet to swing 90 into the slot, the sides of the drawer adjacent the panel being provided with longitudinal grooves, and lugs on the panel to extend 95 into the grooves when the panel is closed, so as to limit the movement of the drawers, and whereby the panel may be swung to an open position to allow the drawers to be totally removed from the cabinet, each drawer having a grate like frame therein provided 100 with openings to form compartments so as to hold groups of coins therein, in stacks of 105 predetermined amounts.

In testimony whereof we affix our signatures.

JOHN F. ROSS, JR.
TIMOTHY C. BILLUPS
